Patented Dec. 11, 1973

229,585

PACKAGING CONTAINER FOR AUDIO- VISUAL CASSETTES

Alan R. Singleton, Croton-on-Hudson, N.Y., assignor to
North American Philips Corporation, New York, N.Y.

Filed June 24, 1971, Ser. No. 156,578

Term of patent 14 years

Int. Cl. D3—02

U.S. Cl. D87—1 D

FIG. 1

FIG. 2

FIG. 3

FIG. 4

FIG. 5

FIG. 1 is a top perspective view of a packaging container for audio-visual cassettes, showing my new design;
 FIG. 2 is a similar view in an open position;
 FIG. 3 is a plan view of the inner box;
 FIG. 4 is a side view of the inner box; and
 FIG. 5 is an end view of the inner box.
 The bottom is plain and unornamented.
 I claim:

The ornamental design for a packaging container for audio-visual cassettes, as shown and described.
